UNITED STATES PATENT OFFICE.

HENRY B. SARGENT, OF NEW HAVEN, CONNECTICUT, ASSIGNOR TO
SARGENT & COMPANY, OF SAME PLACE.

MASTER-KEY CYLINDER-LOCK.

SPECIFICATION forming part of Letters Patent No. 443,261, dated December 23, 1890.

Application filed August 18, 1890. Serial No. 362,263. (No model.)

To all whom it may concern:

Be it known that I, HENRY B. SARGENT, of New Haven, in the county of New Haven and State of Connecticut, have invented a new 5 Improvement in Master-Key Cylinder-Locks; and I do hereby declare the following, when taken in connection with accompanying drawings and the letters of reference marked thereon, to be a full, clear, and exact description of the same, and which said drawings constitute part of this specification, and represent, in—

Figure 1, a view in front elevation of a master-key cylinder-lock constructed in accordance with my invention; Fig. 2, a view thereof in side elevation; Fig. 3, a view showing the lock-case in vertical central longitudinal section and the cylinder in side elevation; Fig. 4, a view of the lock in transverse section on the line *a b* of Fig. 3; Fig. 5, a detached plan view of the cylinder; Fig. 6, a similar reverse view thereof with the tumblers removed; Fig. 7, a detached view in front elevation of one of the tumblers; Fig. 8, a 25 similar detached plan view; Fig. 9, a view in side elevation of the master-key; Fig. 10, a similar view of the pass-key.

My invention relates to an improvement in master-key locks, the object being to produce 30 a simple, compact, and reliable lock of that type; and the invention consists in the construction, as hereinafter described, and particularly recited in the claims.

As herein shown, the lock-case is cast in one 35 piece, and consists of a circular beveled face-plate *A*, provided near its lower edge with a circular opening *B*, a sleeve *C*, extending rearwardly from the face-plate in line with the said opening thereof, than which it is 40 made smaller in internal diameter, so as to form the annular bearing-shoulder *D* between them, a web *E*, located centrally above and parallel with the sleeve *B* and provided with a series of small circular chambers *E'*, opening at their inner ends into the sleeve *C* and closed at their upper ends by a removable cap *F*, and with two perforated lugs *G G*, by means of which the lock-case is secured in place.

50 The cylinder *H*, which is located in the sleeve, is provided at its forward end with a flange *H'*, which fills the opening *C* in the face-plate and bears upon the shoulder *D* thereof to prevent the cylinder from being pushed inward. A washer *H²*, secured to the rear end 55 of the cylinder by means of a screw *H³*, engages at its edges with the rear end of the sleeve and prevents the cylinder from being moved forward, the said flange and washer thus preventing the cylinder from longitudinal movement in the lock-case, but permitting it to be freely rotated therein. The said cylinder is provided with two parallel longitudinal key-slots *H⁴* and *H⁵*, extending throughout its length and through the flange 60 at its forward end and opening into its lower edge, and with a series of transverse tumbler-slots *H⁶*, also opening into its lower edge and intersecting the said key-slots, the said tumbler-slots being centrally enlarged on circular 65 lines, as at *H⁷*. The said cylinder is further provided with a straight series of independent radial circular locking-pockets *H⁸*, formed in its edge opposite the key and tumbler slots and arranged in alignment with the latter. 70 The tumblers, which are located in the said transverse tumbler-slots, each consist of a central stem *I* and two fingers *I'* and *I²*, respectively projecting in opposite directions therefrom. The stems of the tumblers have bearing 75 in the enlarged central portions of the tumbler-slots, to which they conform in cross-section, and project at their upper ends into the locking-pockets *H⁸*, before mentioned, while the fingers of the tumblers respectively 80 extend across the key-slots *H⁴* and *H⁵* in position to be acted upon by the pass-key *J* and the master-key *J'*. Plugs *H⁹*, inserted into the outer ends of the enlarged central portions *H⁷* of the tumbler-slots, retain the tumblers in 85 place therein. The lock will therefore have two series of fingers, either of which will operate the tumblers under the influence of an appropriate key. One of these series of fingers will be duplicated in all of the locks of 90 the series designed to be opened by the same master-key and the other series differentiated in each lock, so as to respond only by a pass-key fitting only one of the locks.

As herein shown, the series composed of 100 the fingers *I²* of the respective tumblers are duplicated, and the series made up of the

5 fingers I' of the tumblers differentiated; but, if desired, this arrangement may be reversed, although it will perhaps be more convenient to have the pass-key, which is most often used, enter the right-hand key-slot II⁴, and the master-key the left-hand key-slot II⁵, as herein provided for.

10 A series of locking-pins K, located in the lower ends of the small chambers E', before mentioned, are suited in length to the differentiation of the fingers I' of the tumblers with which they co-operate. Normally or when the lock is locked these bolts are entered under the tension of small spiral springs 15 K', located above them in the chambers E', into the outer ends of the locking-pockets II⁸ and engage with the upper ends of the stems I of the tumblers.

20 It will be understood from the foregoing 20 that when the right pass-key is inserted into the right-hand key-slot II⁴ of the cylinder its notches will co-operate with the right-hand series of fingers I', so as to lift all of the tumblers, and therefore lift all of the locking- 25 pins and retire them wholly within their chambers in the lock-case, whereby the cylinder is permitted to rotate. As soon, however, as the key is withdrawn the springs K' immediately throw the pins back into the locking-pockets II⁸ of the cylinder, when the same 30 is rotated to bring the said pockets into alignment with the small chambers E', thus re-locking the cylinder against rotation. The pass-key J being adapted in the conformation 35 of its notches to the differentiation of the series of fingers I' of one particular lock in the series will unlock no other lock therein. Inasmuch, however, as the series of fingers I² is duplicated in all of the locks of the series, 40 all of the locks therein may be unlocked by the same master-key J'. I have thus secured a very simple and compact form of lock of the master-key type.

45 If desired, the transverse tumbler-slots may be located on the opposite side of the cylinder from the longitudinal key-slots and the independent locking-pockets dispensed with, in which case the plugs II⁹ would not be used and the enlarged portions II⁷ of the tumbler- 50 slots left open to receive the locking-pins. Other like departures from the construction herein shown and described might be made. I would, therefore, have it understood that I do not limit myself to the exact construction 55 and arrangement of parts herein shown and

described, but hold myself at liberty to make such changes and alterations as may fairly fall within the spirit and scope of my invention.

Having fully described my invention, what I claim as new, and desire to secure by Letters Patent, is—

1. A cylinder-lock having its cylinder provided with two parallel independent longitudinal key-slots without connection between the two slots and each of the two slots adapted to receive its own individual key, substantially as described.

2. A cylinder-lock having a tumbler consisting of a stem and two fingers respectively extending in opposite directions therefrom, substantially as described.

3. A master-key lock having its cylinder provided with two parallel longitudinal key-slots respectively designed to receive a pass and a master key and with a series of transverse tumbler-slots, each intersecting both of the key-slots, substantially as described.

4. A master-key lock having its cylinder provided with two parallel longitudinal key-slots respectively designed to receive a pass and a master key and with a series of transverse tumbler-slots intersecting the said key-slots, and a series of tumblers located in the said tumbler-slots and each consisting of a central stem and of two fingers respectively extending in opposite directions therefrom across the key-slots, substantially as described.

5. In a master-key lock, the combination, with the lock-case, of a cylinder provided with two parallel longitudinal key-slots respectively designed to receive a pass and a master key and with a series of transverse centrally-enlarged tumbler-slots intersecting the said key-slots, a series of tumblers, each consisting of a stem and two fingers respectively extending in opposite directions across the key-slots, and a series of spring-actuated pins located in suitable chambers formed in the lock-case and normally engaged with the cylinder to hold the same against rotation, substantially as described.

In testimony whereof I have signed this specification in the presence of two subscribing witnesses.

HENRY B. SARGENT.
